DEVICE FOR INDICATING ENURESIS TO
PREVENT BED WETTING

Frank H. Jacobson, Minneapolis, Minn.

Application November 17, 1941, Serial No. 419,419

6 Claims. (Cl. 118—138.1)

This invention relates to a device for preventing enuresis or bed wetting. Many people, particularly children, are inclined to urinate at night and wet their night clothes and the bed clothes, which is undesirable. It is an object of this invention to provide a simple and convenient device which can be attached to the body of the person or patient and which will sound an alarm as soon as the urinating begins so that the person will be awakened and can have relief before the night clothes or bed clothes are seriously wetted.

It is a further object of the invention to provide such a device in which a thin flexible material such as crepe paper having substantial tensile strength when dry, but having substantially no tensile strength when wet, is used to hold a movable member in position together with resilient means urging said member to move to rupture said material and engage a pair of electrical contacts to sound an alarm.

It is still further an object of the invention to provide such a device as set forth in the preceding paragraph, said device being enclosed in a casing having an open side through which said flexible material is exposed together with means for holding said casing against the body of the patient with said opening or open side adjacent the urinating organ.

These and other objects and advantages of the invention will be fully set forth in the following description made in connection with the accompanying drawing in which like reference characters refer to similar parts throughout the several views and in which—

Fig. 1 is a top plan view of the casing used with the device;

Fig. 2 is a partial vertical section taken on line 2—2 of Fig. 3;

Fig. 3 is a horizontal section taken on line 3—3 of Fig. 2 as indicated by the arrow;

Fig. 4 is a view in end elevation as seen from the right of Fig. 3;

Fig. 5 is a view of the means for holding the device on the body of the patient, parts of the device being shown in dotted lines; and

Fig. 6 is a wiring diagram shown showing the arrangement of the device.

Referring to the drawing, a device is shown comprising a frame 10 formed as a hollow member and comprising a guideway for a member 11 arranged to reciprocate herein. Frame 10 has a rounded or semi-cylindrical end portion 10a. A screw 12 extends between the sides of member 10 having its head countersunk therein and said screw has mounted thereon a sleeve or cylindrical

block 13. Member 11 is provided at one end with a head portion 11a, the end of which is also rounded or of convexly curved form. Member 11 is bifurcated and has extending between the sides 5 or bifurcations thereof cross pieces or ribs 11b and 11c. A resilient means is provided adapted to engage frame member 10 and member 11 for causing movement of the latter and while various means could be used, in the embodiment of the invention illustrated, a rubber band 14 of common form is shown having its bight ends extending about the block 13 and extending to and around the cross piece or rib 11b. Block 13 and rib 11b are provided with suitable grooves 13a and 11d in which the strands of said rubber band seat to hold said strands in place and prevent lateral movement thereof. A sheet or strip of thin flexible material 15 is wrapped around the end 11a of member 11, the same extending around the 10 end portion 10a of the frame 10. While various materials might be used, it is essential to have a material which has substantial tensile strength when dry but substantially no tensile strength when moistened or wet. The material should 15 also have little or no stretch when under tension. In practice a common thin crepe paper has been found very suitable. Material 15 may be wound about in several layers or one or more layers may be used and the edges connected by a clip, an adhesive or any other suitable means. Another screw 16 extends between the side portions of frame 11 having its head countersunk therein and a member or block 17 is carried by this screw. Block 17 is made of insulating material and is 20 engaged by one end of an electrical contact member 18, the same having a curved or convexly curved cam-like end 18a. A block 19 of insulating material engages the opposite side of contact 18 and a second electrical contact member 20 is provided shown as of rectilinear form and having a portion spaced from the end of contact member 18. Screw 16 passes through contact members 18 and 20 as well as the member 19 and holds the same in place.

25 A casing 21 is provided enclosing the parts described, in which casing frame member 10 is disposed. While casing 21 could take different forms in the embodiment of the invention illustrated it is of general rectangular form in plan having its corners curved and the sides thereof converging to substantially a point or line at its other end. Said casing is open at its lower side and has an opening 21d at its top. At one end 30 of opening 21d a portion 21b extends downwardly

in curved form to receive end portion 10a of member 10 with material 15 therein.

Suitable electric conductors 22 and 23 are connected respectively to the contacts 18 and 20 and these extend through openings in frame member 10 and housing 21 preferably in the form of an electric cord 22a as shown in Fig. 4. A strap or band 26 of fabric or other suitable material is secured to housing 21 as by the snap fasteners carried by said band, said fasteners entering openings 21c. Band 26 is connected at one end to a belt 28 also of fabric or similar material which is adapted to extend about the waist of the person or patient. Band 26 is shown as divided and having portions 26a adapted to extend around the legs of the patient, the ends of portion 26a also being connected to the belt 28.

The conductors 22 and 23 connected to the contacts 18 and 20 will be connected to an alarm device 30. This may be an ordinary alarm bell, buzzer or other suitable electrically operated alarm. A battery or other source of current 31 is disposed in conductor 23 to furnish the necessary current. The cord with conductors 22 and 23 extends from the device and the other parts can be suitably disposed in or adjacent the bed in which the patient is sleeping. It will be noted that a large area of the material 15 is exposed through the open side of casing 21.

In operation, the paper 15 will be placed in position with member 11 in retracted position. The unit comprising parts 10 to 20 will then be slipped into place in casing 21 on portion 21b. The device will be secured upon the body of the patient with the open side of housing 21 against the said body so that the exposed portion of the material 15 is closely adjacent to or directly in front of the urinal organ. Should the patient start to urinate in his sleep, the material 15 will be wetted and the resilient means 14 will then move member 11, rupturing the material 15. Member 11 in its movement will cause the rib 11b, which as shown in Fig. 2, has a cam-shaped or bicuspid form to engage the portion 18a of contact 18 and move the same toward and into engagement with contact 20. This will close a circuit through the alarm device 30 and the alarm will be operated and this will awaken the patient. The patient being thus awakened can control further urinating and have relief before there is any serious wetting of the clothing or bed clothes. After each operation the device can be readily arranged for another operation by placing thereon another piece of the material 15 which holds the member 11 in retracted position. Portion 11a is made of greater width than the adjacent parts to hold sheet 15 away from the latter, as said sheet might exert some friction when wetted. The portions 10, 11 and 21 are preferably made of plastic, glass or glass-like material.

From the above description it will be seen that I have provided a very simple, easily operated and highly efficient device of the character described. The device is of comparatively small size and can be worn by the patient without any discomfort. The device operates quickly at the very first part of the urinating operation and is positive in its operation and in awakening the patient. The device has been amply demonstrated over a long period and found to be very successful and efficient.

It will, of course, be understood that various changes may be made in the form, details, arrangement and proportions of the parts, without departing from the scope of applicant's inven-

tion, which generally stated, consists in a device capable of carrying out the objects above set forth, in the parts and combinations of parts disclosed and defined in the appended claims.

5. What is claimed is:

1. A device for preventing bed wetting having in combination, a frame, a member reciprocable longitudinally in said frame, a piece of flexible sheet material having substantial tensile strength 10 when dry but having substantially no tensile strength when wet extending about said member and a portion of said frame, a resilient means engaging said frame and member acting to move said member longitudinally and against the resistance of said material, an electrical contact on said frame, a second electrical contact movable into engagement with said contact by movement of said member, means for supporting said device on the body of the patient with said material adjacent the urinating organ so that when said material is wet or moistened said member will be reciprocated and will rupture said material and engage said contacts to sound an alarm.

2. A device for preventing bed wetting having 25 in combination, a frame, a member longitudinally reciprocal in said frame having an end portion, a piece of flexible sheet material having substantial tensile strength when dry but substantially no tensile strength when wet extending in looped formation about said end portion of said member and a portion of said frame, a resilient means engaging said frame and said member acting to move said member against the resistance of said material, an electrical contact on said frame, a second electrical contact adapted to be moved 35 into engagement with said first mentioned contact by movement of said member, a housing enclosing said parts on which said frame is carried, said housing having an opening exposing said sheet material and means for holding said device on the body of the patient with said opening in close proximity to the urinating organ whereby when said flexible material is wetted said member will move longitudinally and rupture said material and move said contacts into engagement to sound an alarm.

3. A device for preventing bed wetting having 40 in combination, a frame, a member reciprocable in said frame having an end portion, a piece of flexible sheet material having substantial tensile strength when dry but substantially no tensile strength when wet wrapped in looped formation about said end portion of said member and a portion of said frame and enclosing the same, a rubber band engaging said frame and having a portion passing around one end of said member and being under tension acting to move said member against the resistance of said material, an electrical contact on said frame, a second electrical contact spaced from said first mentioned contact and having a portion adapted to be engaged and moved by a portion of said member when the latter is moved for engaging said contacts, an alarm device, a source of current 45 and an electrical circuit including said alarm, said source of current and said contacts, a casing enclosing and supporting said parts and having an open side through which said material is exposed and means for holding said casing on the body of the patient with said open side adjacent the urinating organ whereby when said material is wet or moistened said member will rupture the same and move said contacts into engagement to sound said alarm.

4. A device for preventing bed wetting having

in combination, a frame having a guideway therein, a member having a portion movable longitudinally in said guideway and having a rounded end portion, said frame having a semi-cylindrical portion spaced from said end portion, a piece of thin flexible material having considerable tensile strength when dry but having substantially no tensile strength when wet wrapped in the form of a loop around said end portion, enclosing said member and frame and said semi-cylindrical portion and holding said member in position, resilient means engaging said frame and said member and tending to move said member against the resistance of said material, an electrical contact on said frame, a second electrical contact spaced from said contact and having a curved cam portion, said member having a portion adapted to engage said last mentioned portion to move said contacts into engagement, a casing enclosing said parts in which said frame is carried, said casing having an open side and means extending about the body of the patient for holding said housing against said patient with said open side adjacent the urinating organ, said flexible material being exposed at said open side so that when the same is wetted said member will be moved to rupture said material and engage said contacts for sounding an alarm.

5. The structure set forth in claim 4, said re-

silient means comprising a rubber band engaging said member and a portion of said frame, said portion being disposed between said rounded end of said member and said semi-cylindrical portion of said frame.

6. A device for preventing bed wetting having in combination a frame, a member reciprocal longitudinally in same frame, a piece of flexible sheet material having substantial tensile strength when dry but having substantially no tensile strength when wet, extending about said member and a portion of said frame, a resilient means engaging said frame and member acting to move said member longitudinally and against the resistance of said material, electrical contacts adapted to be brought into engagement upon movement of said member, a housing extending about said frame and parts carried thereby, the same having a flange at one end forming a ledge for supporting said frame and said parts, said housing having an open side through which said material is exposed and means for supporting said housing upon the body of the patient with said open side adjacent the urinating organ so that when said material is wetted said member will be moved to rupture said material and engage said contacts for sounding an alarm.
